HEAT TREATING FURNACE

Harold E. Mescher, Rivera, Calif., assignor to Pacific Scientific Company, San Francisco, Calif., a corporation of California

Application February 21, 1955, Serial No. 489,595

6 Claims. (Cl. 263—21)

This invention relates generally to heat treating furnaces, and the invention has reference more particularly to a novel shaker-hearth-type heat treating furnace.

In shaker hearth furnaces, the work to be heat treated is fed on to a reciprocating hearth, which, through its motion, serves to automatically move the work or parts treated through the furnace. In furnaces of this type as heretofore constructed, it has been difficult to keep the hearth from warping while the work is being fed thereto due to unequal expansion and contraction of different parts of the hearth, the portions of the hearth covered by the relatively cold work or pieces entering the furnace being retained in a relatively cool condition whereas the portions of the hearth not so covered tend to expand owing to the heat of the furnace, thereby causing the hearth to buckle or bulge upwardly making it difficult to maintain a minimum door opening, resulting in an undesired oxidation of the work parts as they pass through the furnace, and also reducing the rate of speed at which the work can be fed through the furnace due to undesired ingress of cold air.

Although the hearth is thus buckled upwardly in the area consisting of the first three or four feet of the hearth within the muffle while work is passing through the furnace, necessitating an unduly wide door opening, this portion of the hearth will assume a flat position between work cycles, i. e., when the work has passed off this part of the hearth and the same becomes uniformly heated and returns to its normal level position. This constant bending and unbending of the hearth results in failure of the sidewalls of the hearth within a relatively short time, due to the formation of cracks which creep all the way across the hearth making the unit inoperative. Attempts have been made in the past to offset this difficulty by inserting a secondary hearth on top of the main hearth, but experience has shown that while such secondary hearth will protect the main hearth, it itself will fail due to buckling within a short time after being put into use.

After carefully studying the problem, I have found that the reason for the warping is the chilling effects taking place on the floor of the hearth by the cold incoming parts, while the two sidewall upwardly extending retaining flanges of the hearth are maintained at oven temperatures. This condition causes the hearth to move upwardly due to the greater expansion of the flanges than that of the floor of the hearth, which upward movement may amount to two to four inches in the first three or four feet of the hearth within the furnace. Attempts also have been made in the past to employ a series of hearth segments or interconnected plates, which, while serving to prevent excessive heat from reaching the hearth itself, nevertheless make it extremely difficult to employ a minimum door opening owing to the irregular contour of the segments or plates.

It is therefore the principal object of the present invention to provide a novel heat treating furnace of the shaker hearth type having a hearth construction that provides for

2

a minimum door opening in operation, while at the same time ensuring long life of the hearth in use.

Another object of the present invention is to provide a novel heat treating furnace of the above character, so constructed and arranged as to enable easy movement of the work through the muffle of the furnace and having improved hearth actuating means.

These and other objects and advantages of the present invention will become apparent from a perusal of the following specification taken in connection with the accompanying drawings wherein:

Fig. 1 is a longitudinal sectional view in elevation of the novel furnace of this invention.

Fig. 2 is an enlarged fragmentary view of the front of the furnace of Fig. 1.

Fig. 3 is a plan view of that portion of the furnace hearth and associated parts which substantially project in front of the furnace, and Fig. 3(a) shows a portion of the hearth that is located inwardly of the furnace.

Fig. 4 is a view in side elevation of the structure of Fig. 3.

Fig. 5 is an enlarged view of a portion of the hearth designated by the lines 5—5 of Fig. 1.

Referring now more particularly to the drawings, the reference numeral 1 designates the shell or casing of the furnace which is internally lined with heat insulation 3 shown surrounding heating elements 39 adapted for heating a muffle or oven 2 contained within the furnace shell. Shown within the muffle 2 is the primary or main hearth 4 consisting of a longitudinally extending web or plate having upstanding continuous side flanges 4'. The primary hearth 4 is supported for swinging forward and rearward movement by means of hangers 5 having the shape of rods with bent over upper ends supported upon transverse rods 6 extending across the muffle 2 within the same. The lower ends of the hangers 5 extend across the hearth 4 and beneath the same and support the hearth by means of angle bars 7 welded to the bottom of the hearth. Arcuate retaining plates 8 are welded at one side of an edge of the angle bars 7 and serve to retain the hanger rod 5 within the angle bar 7 while permitting relative turning movement of the hanger rod within the angle iron.

In order to actuate the hearth in use, the underside of the hearth near the forward end thereof is provided with a transverse shaft 9 welded thereto, which shaft extends beyond the sides of the hearth 4 and has its end portions turnably mounted in apertures provided in depending links 10 and 10', the upper ends of which links are turnably supported upon studs 11 carried by frame 12 of the furnace. The lower ends of the links 10 and 10' carry a follower shaft 13 on which is mounted a follower roller 14 for cooperating with a step cam 15 fixed upon a cam shaft 16 having its ends mounted in bearings 17 carried by the frame 12. One end of the cam shaft 16 has a sprocket 18 thereon driven by a sprocket chain 19 driven in turn by a motor 20.

The primary hearth 4 is urged inwardly of the furnace by coil springs 21 and 21' which are connected to brackets 22 fastened to the forward end of the hearth flanges 4' and also connected to washers 23 loosely fitting and adjustable along rods 24 fixed upon frame 12. Thus, in use, by adjusting the washers 23 along the rods 24, the relative tension of the springs can be varied to determine the rapidity of movement of the hearth 4 and the rate at which the work will feed over this hearth. As the motor 20 turns, the step cam 15, acting through the roller 14 and the follower shaft 13, will move the links 10 and 10' forwardly against the tension of springs 21 and 21', and hence move the hearth forwardly since these links are connected to the hearth via the transverse shaft 9. As the roller 14 rides off the step of the cam 15, the springs 21 and 21' will move

the hearth rearwardly suddenly until the bumper block 25 on the hearth abuts the cushioned stop 26 carried by the frame 12. Thus, each time as the springs move the hearth rearwardly, or towards the left as viewed in Fig. 1, the work thereon is advanced into the furnace. The springs 21, 21' do not extend parallel to the sides of the hearth 4, but extend outwardly at equally inclined angles thereto, as shown in Fig. 3, thereby not only serving to urge the hearth rearward with the desired tension, but also serving to retain the hearth centered within the muffle 2 during its swinging movements. During the swinging movement of the hearth forwardly and rearwardly, the same is supported upon the hangers 5 which pivot on the shafts 6 extending across the muffle 2.

The furnace muffle is provided with an entrance door 27 that may be raised or lowered with respect to the hearth 4 to vary the input opening of the muffle. In order to prevent undesired oxidation of the work within the furnace, it is desired that the lower edge of the door 27 be positioned as close to the top of the hearth 4 as practicable, and hence it is essential that the hearth 4 remain truly horizontal at all times in use. To prevent the buckling of the hearth, the same is provided with a series of consecutive protective shingles or cover plates 28, 29, 30, 31, 32 and 33. These shingles or protective cover plates are formed with a flat bottom plate and upstanding side flanges and are telescoped one into another, as shown in the drawings, and serve to overlie the upper surface of the primary hearth 4 in heat protecting relation. Thus, shingle 28, for example (see Figs. 3 and 4), is provided with side flanges 34 adjacent primary hearth flanges 4', and this shingle is made narrower at its rear end than at its forward end, so that its rear end will project somewhat into the forward and wider end of shingle 29, in overlapping relation, as especially shown in Fig. 3, thereby providing a wedge-shaped insulating dead air space between the shingle and the main hearth 4. The forward end edges of the shingles are welded along their flat bottoms, as indicated at 38, to the primary or main hearth 4, and this is the only place at which the shingles are attached to the main hearth. Thus, it is noted that each of the shingles, with the exception of the innermost shingle 33, is narrower at its rear end than it is at its forward end, so that these shingles will telescope one within the other, and, since these shingles are only attached to the main hearth 4 at their forward ends by the weld 38, they are free to thermally expand and contract without warping or buckling in use, as their unattached rear ends permit varying telescoping movement to compensate for temperature changes and also aid in moving the work rearwardly in the furnace. The insulating wedge-shaped dead air spaces between the shingles and the main hearth prevent heat from escaping from the main hearth to the shingles and thence to the cold incoming work.

These shingles or plates cover the main or primary hearth 4 in that region within the muffle where the work is introduced, i. e., the forward portion of the muffle, and where the work is necessarily cold. Such shingles forming the wedge-shaped dead air spaces thereunder prevent undue thermal expansion and contraction of the forward portion of the main hearth 4, since they thusly protect this portion of the hearth against the chilling effect of the newly entering work, so that the main hearth is uniformly heated by the furnace at all times and retains its plane truly horizontal shape, enabling the door 27 to have a minimum opening at all times during the operation of the furnace, thereby keeping out undesired air and retaining proper atmospheric conditions within the muffle 2. This desired atmospheric condition is further enhanced by use of a gas flame supplied by the burner 36 located below the door 27. By the time the work has left the last shingle 33, it has reached

the temperature of the furnace, and hence it does not cause any warping or distortion of the rear portion of the main hearth 4. Since the shingles telescope one within the other, they are free to expand and contract by the telescoping action without stress being set up in the shingles, so that the novel hearth of this invention has an extremely long life in use. The heated work leaving the end of the main hearth is shown dropping into a quench tank 37. The rear end of the muffle is shown closed by a rear removable plug 35 having a vent 39' and a thermocouple control 40.

Since many changes could be made in the above construction of the furnace and many apparently widely different embodiments of this invention could be made without departing from the scope thereof, it is intended that all matter contained in the description or shown in the accompanying drawings shall be interpreted as illustrative and not in a limiting sense.

What is claimed is:

1. A heat treating furnace comprising a muffle, a shaker hearth extending longitudinally within said muffle and being mounted for reciprocating movement therewithin, said shaker hearth comprising a main hearth web and a plurality of successive shingles carried by said main hearth web, each of said shingles being affixed at one end only to said main hearth web and overlapping an adjoining shingle at its other end for relative telescoping movement with said adjoining shingle, thereby to compensate for thermal expansion and contraction of the shingles without buckling thereof, the overlapping of said shingles providing consecutive dead air spaces between said main hearth and said shingles for preventing the chilling of said main hearth by cold work passing over said shingles, thereby preventing buckling of said main hearth.

2. A furnace of the character described, comprising a casing, a muffle within said casing and insulated therefrom, a shaker hearth within said muffle and extending longitudinally thereof, hangers supporting said shaker hearth for longitudinal oscillatory movement within said muffle, said shaker hearth comprising a main web having consecutive overlapping shingles, said shingles providing wedge-shaped dead air spaces between the same and said main web for heat insulating the latter, motor means connected for moving said hearth intermittently forwardly with respect to said muffle, and spring means connected for urging said hearth intermittently rearwardly with respect to said muffle, said spring means comprising a pair of springs connected to the forward end of said hearth and extending rearwardly and outwardly for also centering said hearth within said muffle while at the same time urging the hearth rearwardly against the action of said motive means for moving the work rearwardly within the muffle in steps.

3. A furnace as defined in claim 2 wherein the said shaker hearth main hearth web extends longitudinally within said muffle and outwardly of the forward end thereof and said successive telescopic shingles overlie said main hearth web only in the forward portion of said muffle, said shingles being respectively affixed to said main hearth at their forward ends only and serving, in conjunction with said wedge-shaped dead air spaces, to retain said main hearth at uniform temperature, preventing the buckling and distortion of the same in use, the rearward ends of said shingles by their telescoping action permitting thermal expansion and contraction thereof without any buckling of the shingles while, at the same time, the rear edges of said shingles aid in moving the work rearwardly.

4. A heat treating furnace comprising an elongated casing, a muffle extending longitudinally within said casing and insulated therefrom, means interposed between said muffle and its insulation for heating said muffle and contents, a shaker hearth having a flat bottom plate and side flanges extending longitudinally within said muffle

and projecting outwardly through the forward open end thereof, spaced hangers for pivotally supporting said shaker hearth within said muffle, protective non-buckling shingle members overlying said hearth plate and providing dead air spaces between the hearth plate and the shingles for preventing work handled by said furnace from chilling said hearth plate and buckling the same, motor driven cam and follower means for intermittently moving said hearth forwardly within said muffle, and spring means for intermittently moving said hearth rearwardly within said muffle to effect movement of the work within said muffle.

5. A heat treating furnace as defined in claim 4 wherein said spring means comprises tension springs connected to the forward sides of said hearth and extending rearwardly and outwardly of said hearth, and connected to said casting for also automatically centering said hearth within said muffle.

6. A heat treating furnace as defined in claim 4 wherein said protective non-buckling shingle members comprise shingles overlying the forward portion of said hearth,

said shingles being attached to said hearth at their forward ends only, with their rear ends telescoping onto the forward ends of adjoining shingles thereby to allow for thermal expansion and contraction of said shingles without bending or buckling thereof in use, while providing wedge-shaped dead air spaces between said shingles and said shaker hearth to heat insulate the latter from the cold incoming work.
